INVENTOR
Jacob Rudges
BY *John J. Gilderman*
ATTORNEY

UNITED STATES PATENT OFFICE

JACOB RUDGES, OF HOLLIS, NEW YORK, ASSIGNOR, BY MESNE ASSIGNMENTS, TO NOMA ELECTRIC CORPORATION, OF NEW YORK, N. Y., A CORPORATION OF NEW YORK

DECORATIVE DEVICE.

Application filed October 5, 1927. Serial No. 224,102.

This invention relates to decorative devices.

A feature of the invention is the provision of means whereby an ornamental element, such as a candle holder, or an electric light, simulating such candle holder and its light, or any ornamental device of this character, is easily secured to or detached from a bar, rod, or any supporting device of substantially small cross-sectional periphery. By this means, it is possible to associate, in any number of relative positions, any number of ornamental units with respect to the bar, rod, or device to be ornamented.

In the particular construction shown on the drawing and made a part of this specification, the invention is seen to be embodied in the attachment of an electric lighting unit of ornamental character to a wreath of the type customarily used at Christmas time. However, it is to be understood that the scope of the invention is not to be limited to this particular embodiment.

One of the objects of this invention is to provide an improved means for securing to a part to be ornamented an ornamental element, such as an electric lighting device, or the like.

A further object of this invention is to provide an improved decorative device of the type used for display purposes with which a lighting attachment is associated in a neat and simplified manner, which provides an arrangement comparatively inexpensive to assemble, and which forms a harmonious, ornamental unit.

A further object of this invention is to provide an improved ornamental lighting attachment which is adapted to be easily and conveniently mounted, comprises few parts, possesses a great deal of flexibility for utilization in various ways, is inexpensive to manufacture, and is withal efficient to a high degree in use.

Other objects of this invention will in part be obvious and in part hereinafter pointed out.

The invention accordingly consists in the features of construction, combinations of elements, and arrangement of parts which

will be exemplified in the construction hereinafter described, and of which the scope of application will be indicated in the following claims.

In the accompanying drawing, in which is shown one of the various possible illustrative embodiments of this invention,

Fig. 1 is a view in elevation of an embodiment of the invention.

Fig. 2 is a vertical sectional detail view on the lines 2—2 of Fig. 3, disclosing specific features of the invention.

Fig. 3 is a horizontal sectional view taken on line 3—3 of Fig. 2.

Referring in detail to the drawing, 10 denotes a decorative device, here shown as a wreath, embodying the invention. Said wreath may be of any suitable shape, but is here shown as being of the type displayed on doors and windows at Christmas time with the conventional annular body portion 12.

Secured to said body portion of the wreath is an ornamental element of any desired character, here shown as the lighting element 14, upstanding from said body portion, and extending into the opening formed by annular portion 12. Element 14 may have the electric lamp 16 mounted therein, so positioned that it will be located at the center of wreath 10. A suitable power source may be conveniently connected to said lamp through the lighting element 14 by means of the duplex conductor 18 to which a customary electrical plug 20 is connected.

Lighting element 14 is seen to comprise the lamp base 22 which is made up of the tubular sleeve 24 formed from any suitable material easily shaped to present an ornamental contour, somewhat readily deformable for a purpose hereinafter appearing, yet providing a construction of a substantially rigid member, and having the property of an electrical non-conductor. In the particular embodiment disclosed, the several results recited have been achieved by making sleeve 24 of impregnated paper, wound in the customary spiral form to reinforce the tubular construction of the sleeve. Said

sleeve may be decorated or appropriately colored to harmonize with the wreath 10. Fitted in one end of the sleeve, as by a pressed fit, or the like, is a screw socket or shell 26 for receiving the lamp 16. Said socket may be of any desirable construction to permit the contact wires, 28, 30 of a lead 32, here shown as extending from the duplex cable 18 to connect the lamp 16 to a 10 source of power through the plug device 20.

The lead 32 passes from the end of socket 26 through sleeve 24 and out the end 33 of said sleeve opposite that in which said socket is positioned. Wedged, or fitted snugly in 15 this end of the sleeve is a stopper 34, having a slight taper to facilitate obtaining a tight fit. Said stopper may be of a yieldable material, as, for instance, cork, soft rubber, or the like.

20 Before positioning stopper 34, however, an easily deformable wire 36 is passed diametrically over the smaller end 38 of the stopper. If desirable, a groove may be made across this end but, for the purposes of the 25 construction herein described, such provision has been found unnecessary. The ends 40, 42 of the wire 36 are turned down along the sides of stopper 34. The stopper 34 with the wire 36 so positioned is then inserted 30 through end 33 of sleeve 24, compressing wire 36 and lead 32 against the inner wall 44 of the sleeve. Where the material of sleeve 33 is of a very rigid character, as in the case of some of the condensation products of phenol, a vertical groove 46 may be 35 provided in the side of stopper 34 to receive lead 32. Where the said sleeve is made of impregnated paper, or like elastic substances, no such groove is necessary, since the sleeve 40 itself is capable of sufficient deformation to 45 accommodate the thickness of lead 32. The ends 40, 42 of wire 36, left projecting from sleeve 24 upon the insertion of stopper 34 therein are used for securely fastening said 50 stopper and the sleeve 24 frictionally retained thereon to any device similar in nature to wreath 10, in a manner hereinafter appearing.

Briefly, assembly of the several parts is 55 carried out as follows: The lead 32 is passed through the sleeve 24, and the socket 26 fitted in said sleeve. The wire 36 is then looped over the smaller end 38 of the stopper 34, the central portion of said wire being received 60 in a groove across the top of said stopper, if such be provided. The stopper is then inserted into said sleeve so that the ends 40, 42 of wire 36 project downwardly and outwardly therefrom. The lighting element 14, 65 now assembled, is positioned on wreath 10 with the ends of the wire straddling, and stopper 34 abutting the same. Said ends of wire 36 are then twisted down around the adjacent portion of the wreath body 12, and 70 then upward, the wires passing in reverse

directions toward the lamp base. Said ends are finally twisted in reverse relative direction about the sleeve. Owing to the flexibility of the lamp base construction, the assembling may be done with the maximum 70 ease and rapidity, leaving the lighting attachment thus securely fastened to the body of the wreath.

It will thus be seen that there is provided a device in which the several objects of this 75 invention are achieved, and which is well adapted to meet the conditions of practical use.

As various possible embodiments might be made of the above invention, and as various 80 changes might be made in the embodiment above set forth, it is to be understood that all matter herein set forth or shown in the accompanying drawing is to be interpreted 85 as illustrative and not in a limiting sense.

Having thus described my invention, I 90 claim as new and desire to secure by Letters Patent:

1. In a device of the character described, the combination with a decorative body portion, of an attachment secured to said body, said attachment including a sleeve, an electrical fitting attached to one end of said sleeve, a stopper fitted in an end of said sleeve, and a wire having an intermediate 95 portion overlying the inner end of said stopper, and having its ends projecting outward between said stopper and said sleeve, said ends being twisted around an adjacent portion of the said body to secure the attachment thereto. 100

2. In a device of the character described, the combination with a decorative body, of an ornamental attachment secured to said body, said attachment including a sleeve, a 105 socket fitted in one end of said sleeve, a stopper in the other end of said sleeve, a wire engaging said stopper and twisted around said body to secure the attachment thereto, said sleeve being flexible and conductor wires connected to said socket and extending out of said sleeve thru said other end. 110

In testimony whereof I affix my signature.

JACOB RUDGES.
